UNITED STATES PATENT OFFICE.

DAVID KAUFMAN, OF NEW YORK, N. Y.

PROTECTIVE APPARATUS FOR BANK WINDOWS AND THE LIKE.

Application filed March 10, 1925. Serial No. 14,534.

To all whom it may concern:

Be it known that I, DAVID KAUFMAN, a citizen of the United States, and a resident of New York, in the county and State of New York, have invented an Improvement in Protective Apparatus for Bank Windows and the like, of which the following is a specification.

This invention relates to protective apparatus for bank windows, cash booths and the like and more particularly to such apparatus adapted for protection in case of hold-up.

One of the objects of the invention is to provide apparatus of the above nature of simple and practical construction and efficient action. Another object is to provide apparatus of the above nature adapted to operate positively and quickly and serve as a dependable protection against a sudden holdup. Other objects are to provide such apparatus which is conveniently installed and adapted to the condition of practical use, and which when not being operated is unobtrusive and substantially unnoticeable.

Other objects will be in part shown or in part pointed out hereinafter.

The invention accordingly consists in the features of construction, combination of elements and arrangements of parts which will be exemplified in the structure hereinafter described and the scope of the application which will be indicated in the appended claims.

In the accompanying drawing in which are shown one or more possible embodiments of the several features of this invention.

Figure 1, is a rear elevation showing the apparatus applied to a bank window and in open position, the window being of the type having one opening only.

Figure 2, is a rear elevation showing the apparatus applied to a window having a lower opening and an upper opening, certain details not shown in Figure 1 being included,

Figure 3, is a vertical section taken along the line 3-3 of Figure 2,

Figure 4, shows somewhat diagrammatically a series of windows fitted with the apparatus and means for joint operation,

Figure 5 is an end view looking from the left of Figure 4,

Figure 6 shows in perspective a portion of the apparatus in closed position, and

Figure 7 shows in section a device for actuating the apparatus.

Similar reference characters refer to similar parts throughout the several views 60 of the drawing. Referring now in detail to the drawing,

1 represents the body of a shield, guided by slides 2, 3, and held in open position by a latch 4, said latch being pivoted on a yoke 65 5, and held under the protruding lip 6 of the shield 1 by the spring 7.

A wire 8, coming from an electric meter tapped by the switch 9 and the fuse 10, is connected to the tongue 11 of the jack 12. 70 A wire 13, coming from the opposite pole of the same meter, is tapped by the plug 14 and the fuse 15 and is then connected to one of the poles of the motor 16.

The wire 17 connects the motor 16 and the 75 upper prong of the jack 12, the lower prong of which by means of the wire 18 tapped by the switch 19 is connected to one pole of an electrical alarm gong 50, the other pole of which is connected to the wire 13 by means 80 of a wire 20.

When the shield 1 is in open position, the finger 21 holds the tongue 11 of the jack 12 in contact with the upper prong of the said jack 12, (Figs. 1, 2) but when the shield 1 85 is closed, the tongue 11, made of springy metal, returns to its natural position resting upon the lower prong of the jack 12.

21 represents an arm bend carrying a metal tube 22 having one end closed and the other sealed with insulating material embracing the wires 24, 25. The terminals of said wires 24, 25 are connected to an electrical plug 26. The other terminal of the wire 24 projects into the inside of the tube 95 22 and the other terminal of the wire 25 is firmly connected to said tube 22 having a metal plunger 27 floating therein. Fig. 7.

In operation the plug 14 is locked with plug 26, the switches 9, 19, are closed and 100 the bend 21 is strapped to the arm of the cashier, in a position so as to cause the floating piece 27 to rest against the sealed end of the said tube 22. Fig. 7.

Suppose a robber should enter a bank, and 105 standing before the window of the cashier, levels a revolver at his head and commands him to put up his hands, or hand over the money; if told to throw up his hands, by doing so he causes the floating piece 27 to 110 fall upon the wires 24, 25 of the tube 22, closing the motor circuit; said motor 16 be-

ing thus energized rotates and the lever 28 carried by the shaft of the motor 16, butts against the latch 4 releasing the shield 1, the springs 29, 30 no longer held stretched, 5 contract pulling downward the shield 1 closing same.

If however the cashier is told to hand over the money, while appearing to do that, with his foot he can raise the pedal 31 causing 10 the wires 32, 33 respectively connected to the wires 8, 13, to bear upon each other closing the motor circuit. The motor 16 is then actuated and thru the process above stated the shield 1 is released and closed.

15 Said pedal 31 is placed along the floor under the windows; spring 34, holds it in a horizontal position; said pedal 31 can be readily operated by any one standing near said windows. Fig. 4.

20 When the shield 1 is closed, the tongue 11 resting upon the lower prong of the jack 12, completes the alarm circuit and the gong 50 is caused to ring. When the shield 1 is in open position the collapsible cover 35 hinged 25 under spring tension to the said shield 1, is held in a vertical position by the slides 2, 3 (Fig. 2) but as the shield 1 is released and nears its descent, the tongues 36, 37 of the cover 35, forced by the spring embodied in 30 the hinge 51, pass thru the openings 38, 39 of the slides 3, 4, and cause said cover 35 to swing away from the shield 1 and rest upon the surface of the bench 52. Fig. 6.

35 The rear end of the cover 35 has a V shaped wall, the apex of which is central with said cover 35 and faces the front of the shield 1 as shown in Figure 6. When the shield 1 is released, if it should happen that the robber's hand is caught between the bottom 40 of the window and the released shield 1, the burglar in the effort of releasing himself may discharge his revolver, the V shaped wall of the cover 35 will deflect the bullet from its course and prevent possible injury 45 to the cashier.

50 Part of the left side of the shield 1 is toothed in a saw shape, said teeth being engageable with a plunger 40 held in a forward position by the spring 41. It can readily be seen that as soon as the shield 1 is lowered, the plunger 40 by engaging with the teeth

of shield 1 will prevent same from being raised.

In its descent the shield 1, trips the levers 44 connected to the plunger 46 by the rod 55 45. Said lever 44 in action pulls the plunger 46 from under the shields 1^a, 1^b, releases the springs 29, 30 causing the shields 1^a, 1^b to close, it can be easily understood that with this arrangement, one shield 1 is sufficient 60 to operate a series of shields of the type 1^a, 1^b. Fig. 4.

Having thus described the invention what I claim is:

1. In protective apparatus for bank windows and the like, in combination, a bullet proof shield positioned at the rear of said window and slidable vertically, a latch member holding said shield in raised open position, electrically operated means for releasing said latch, means adapted to substantially instantly lower said shield to closed position upon release of said latch, a member hinged to the inner side of said shield adjacent the lower portion thereof, means normally holding said member folded upwardly against said shield, and means adapted upon said shield moving downwardly to permit said member to swing downwardly away from the surface of said shield, said member having a surface adapted to deflect bullets.

2. In protective apparatus for bank windows and the like, in combination, a bullet proof shield positioned at the rear of said window and slidable vertically, a latch adapted to hold said shield in raised open position, electrically operated means for releasing said latch, means adapted upon release of said latch to substantially instantly move said shield downwardly toward closed position, means adapted to prevent raising of said shield from the position in which it comes to rest after release, and means hinged to said shield on the inner side thereof adapted to swing downwardly and close the opening beneath said shield should said shield be prevented from moving to final closed position.

In testimony whereof I affix my signature.

DAVID KAUFMAN.
